US00D881876S

(12) **United States Design Patent** (10) Patent No.: **US D881,876 S**
(45) Date of Patent: **** Apr. 21, 2020**

(54) **SMART WATCH**

(71) Applicant: **Xujia Xiao**, Huangshi (CN)

(72) Inventor: **Xujia Xiao**, Huangshi (CN)

(**) Term: **15 Years**

(21) Appl. No.: **29/715,723**

(22) Filed: **Dec. 4, 2019**

(51) LOC (12) Cl. **14-02**

(52) U.S. Cl.

USPC **D14/344**; D10/32

(58) **Field of Classification Search**

USPC D10/1-2, 5, 10, 14-15, 21, 30-39,
D10/40-41; D14/344; D11/3, 5, 93-94,
D11/99
